UNITED STATES PATENT OFFICE.

ELDON A. EARLE, OF BLOOMFIELD, NEW JERSEY.

DEVICE FOR PROMOTING COMBUSTION.

Application filed October 23, 1925. Serial No. 64,343.

This invention relates to a device for supplying heated air into the fire-box of a furnace closely adjacent the surface of the fuel, whereby the incompletely burned combustion gases which rise from the fuel-bed and usually pass out of the fire-box unburned, are completely consumed, thereby resulting in a more economical operation of the furnace.

One object of the invention is to provide a novel and improved device of the character described, whereby the heated air is diffused or spread over substantially the entire fuel-bed so that practically all of the gases are burned.

Another object is to provide such a device embodying novel and improved features of construction for attaching it to the fuel supply door of a known furnace with a minimum of modification of the door structure and so that the invention may be easily and quickly applied by an unskilled person to, for example, his house-heating furnace.

Further objects of the invention are to provide a device of this character including a conduit or pipe for directing air from outside the furnace to the interior of the fire-box, said conduit having its inner extremity so formed as to efficiently spread or diffuse the air over the fuel-bed and thoroughly heat the air before its delivery into the fire-box; to provide a novel and improved construction whereby the conduit or pipe may be adjustably connected to a furnace door to permit the inner end of the conduit to be adjusted relatively to the fire-box and the fuel supply door so that the device will not interfere with opening and closing of the fuel supply door, and to obtain other results and advantages as may be brought out by the following description.

In the accompanying drawings I have shown the invention embodying details of construction particularly designed for enabling the device to be applied to an ordinary furnace fuel supply door, but it will be understood that this is primarily for the purpose of illustrating the principles of the invention, and that the invention may be connected to the furnace in any suitable manner for supplying air from the exterior

thereof to the interior of the fire-box closely adjacent to fuel-bed.

Referring to said drawings, in which corresponding and like parts are designated throughout the several views by the same reference characters—

Figure 1 is a fragmentary side elevation of a known type of furnace with portions broken away, showing a device embodying the invention applied to the fuel supply door of the furnace;

Figure 2 is an enlarged longitudinal vertical sectional view through the fuel supply door and the device embodying the invention;

Figure 3 is a fragmentary front elevation of the fuel supply door illustrated in Figure 2;

Figure 4 is a view similar to Figure 2 showing a modified form of the invention wherein the conduit or pipe is adjustably connected to the furnace door, and

Figure 5 is a transverse vertical sectional view, taken on the line 5—5 of Figure 4.

Specifically describing the embodiment of the invention illustrated in Figures 1-3, inclusive, of the drawings, the reference character A designates a furnace of known construction including the usual fire-box B at the bottom of which is arranged a grate C and at one side of which above the grate is provided a fuel supply opening D normally closed by a door E. The door E is formed with the usual damper-openings F, but the damper plate which usually controls said openings is removed to enable the device embodying the invention to be secured to the door.

The said device comprises a pipe or conduit 1 having one end flared as at 2 and formed with an annular flange 3. In applying the device 1 to the door, the flange 3 is disposed against the inner side of the door, and bolts 4 pass through said flange and a ring 5 at the outer side of the door, the bolts preferably passing through the damper-openings F to avoid the necessity of drilling special holes for the bolts. In the form of the invention illustrated, the flared portion 2 of the pipe 1 is of a diameter to only partially cover the damper-openings

F, and the portions of the said openings F outside the flange 3 are closed by suitable plates or strips 6 which may be mica, and which are clamped between the flange 3 and the inner sides of the door. Of course, if desired, the flared portion 2 might be made to completely cover the openings F, or in some furnaces the openings F might be so arranged that the flared portion 2 would cover them. The pipe 1 is of a length sufficient to extend into the fire-box B when the furnace door is closed to a substantially central position, and the inner end of the pipe 1 is turned downwardly and provided with an outwardly flared nozzle 7 which is formed with a horizontal annular flange 8 preferably of considerable thickness.

With this construction, it will be observed that when the fuel supply door E is closed, air will enter the pipe 1 through the damper-openings F and be discharged into the fire-box adjacent the top of the fuel-bed and at substantially the center thereof, as shown in Figure 1. The air is heated in its passage through the pipe 1 and is drawn through the pipe by the suction created by the rising hot gases in the fire-box. When the air reaches the nozzle 7 it is spread or diffused over a considerable area of the fuel-bed and the speed of travel of the air is reduced so that it may slowly and gradually mix with the incompletely burned fuel gases rising from the fuel-bed. It will be observed that the flange 8 will always be quite hot, and accordingly the air as it passes upwardly around the flange will be heated to a high degree. The introduction of the heated air as above described results in a substantially complete combustion of the unburned fuel gases which rise from the fuel-bed, so that a saving of fuel is effected as well as a more gradual and uniform production of heat.

In many furnaces the length of the conduit 1 is such that the conduit may swing out of the fuel supply opening D when the door E is opened, and the invention so far described is particularly designed for use with such furnaces.

Where the fire-box is of a large diameter or the fuel supply opening D so small as to prevent the pipe 1 above described from being swung out of the fuel opening and consequently prevent full opening of the fuel supply door, the pipe 1 is adjustably connected to the door in any suitable manner such as shown in Figures 4 and 5. In this form of the invention, a flanged collar 9 is secured to the interior of the fuel supply door G by means of bolts 10 and a ring 11 corresponding to the bolts 4 and the ring 5, shown in Figures 1-3, inclusive. A pipe 12 is longitudinally slidably arranged in the collar 9 and projects entirely through the door G, the outer end of said pipe having

secured thereto a flared inlet nozzle 13, supply of air through which to the pipe 12 is preferably controlled by a butterfly valve 14. To the inner end of the pipe 12 is secured in any suitable manner as by means of a bolt 16, an outlet nozzle 15 which is substantially the same in construction as the nozzle 7 shown in Figures 1-3, inclusive. The pipe 12 is formed of a length sufficient to locate the nozzle 15 at substantially the center of the fire-box of the furnace when the pipe is pushed inwardly of the door G until the inlet nozzle 13 engages the front side of the door, as shown in Figure 4. When it is desired to open the fuel supply door G, the pipe 12 is pulled outwardly of the door a distance sufficient to enable the outlet nozzle 15 to clear the side of the fuel supply opening when the door is swung open, and to limit the outward movement of the pipe 12 to this extent, the collar 9 may be made of the right length to serve as a stop to be engaged by the end 17 of the outlet nozzle 15 and limit outward sliding of the pipe. It will be noted that this adjustable mounting of the pipe 12 also enables the position of the outlet nozzle 15 to be varied relatively to the fuel-bed as may be desired for efficient operation of the furnace.

The supply of air to the fire-box through pipe 1 is in proportion to the rate of combustion and automatically controlled by the flue damper and ash-pit damper. A slow rate of combustion is usually preferable so as to cause slow movement of the heated air through pipe 1 which ensures thorough mixture of the heated air with the gases rising from the fuel-bed, whereby more efficient combustion and a uniform supply of heat is ensured and formation of clinkers in the fire-box prevented.

While I have shown and described two preferred forms of the invention embodying certain details of construction, it will be understood that these details may be modified and changed by those skilled in the art without departing from the scope of the invention. Therefore, I do not desire to be understood as limiting myself except as required by the following claims when construed in the light of the prior art.

Having thus described the invention, what I claim is:

1. A device of the character described, comprising a conduit having means for connection to an opening into the fire-box of a furnace so as to extend into said fire-box and supply air above the fuel-bed, said conduit having its inner end turned laterally downward and flared and having at the end of the flare a broad horizontally projecting annular flange which will be heated from the fire and heat the incoming air as it passes beneath said flange radially outward over the fire.

2. The combination with a furnace having a fire-box with an opening in its wall and a closure for said opening having radially disposed damper openings therein, of a conduit for supplying air from said damper openings to the middle of the fire-box above the fuel bed, said conduit having a flange disposed at the inner side of the closure and crossing the said damper openings between

their ends, a ring arranged at the outer side 10 of the closure opposite said flange, plates between said flange and inner side of the closure covering the radially outer ends of the damper openings, and fastening members extending through said flange, damper open- 15 ings and outer ring.
